CLAIM

The ornamental design for a vehicle cabinet, as shown and described.

DESCRIPTION

FIG. 1 is a perspective view of the first embodiment of the vehicle cabinet of the present invention looking from the upper left;

FIG. 2 is a perspective view of the vehicle cabinet exterior surface of the present invention looking from the upper right in this figure;

FIG. 3 is a perspective view of an alternative embodiment of the vehicle cabinet exterior surface of the present invention with the latch mechanism shown at the opposite side of the door from that of FIG. 1 so that the door opens in the opposite direction from the door of the embodiment of FIG. 1 and,

FIG. 4 is a perspective view of the vehicle cabinet exterior surface of FIG. 3 looking from the upper right in this figure. The rear and bottom of the vehicle cabinet are plain and unornamented and form no part of the claimed design.
